ARCH SUPPORT

Joseph C. Howell, Fort Lee, N. J.

Application February 5, 1934, Serial No. 709,734

9 Claims. (Cl. 36—71)

This invention relates to arch supports of the character employing a supporting plate and means for effecting and maintaining an upward arching or bowing of the said plate.

5 The invention provides an improved arch support which may be readily applied to any style or type of men's, women's or children's shoes and which is so constructed that a wide range of adjustments in the height of the arched portion 10 of the supporting plate may be obtained in order to provide a corrective support for any abnormal condition of the longitudinal or transverse arches of the foot.

The invention further contemplates an arch 15 support including an arch plate which is constructed as to provide relative different degrees of resiliency and flexibility in various portions or areas thereof and with means underlying the arch plate and so connected therewith as to exert 20 stresses thereon between its ends for effecting and maintaining an upward buckling or arching of the plate or portions thereof, while permitting of a sufficient degree of flexing and bending of the plate between its ends so that it yields or 25 gives with the foot to provide a proper and comfortable support therefor.

The invention further provides, in an arch support of the character described, an arch plate composed of a plurality of plies or laminations 30 which are differently contoured and provide varying degrees of resiliency and flexibility at localized areas of the plate with a gradual merging of the varying degrees of flexibility of adjacent areas into each other, the greatest resistance to bending being located adjacent and 35 medially of the side portion which underlies the inner longitudinal arch and with areas of decreasing resistance and increasing flexibility and resiliency extending forwardly, rearwardly and 40 to the opposite side edge of the plate.

A further feature of the invention resides in an arch support which includes a flexible and 45 resilient arch plate having its highest point or area at the side portion which medially underlies the inner longitudinal arch and which decreases in height forwardly and rearwardly thereof and to the opposite side edge of the plate, and which further includes means for adjusting the height.

The invention further comprehends in an arch support, an arch plate which is so fashioned at 50 its forward portion and so connected with a tension plate as to provide a high degree of flexibility in the region of the forward ends of the

inner and outer longitudinal arches where the greatest bending is required.

In addition to providing a comfortable and natural support for the longitudinal and transverse arches of the foot, the invention also provides an arch support including a plate recessed at its forward portion between the opposite sides to accommodate means for supporting and correcting any abnormal condition of the metatarsal arch of the foot.

With the above recited and other objects in view, reference is now made to the following specification and accompanying drawings in which there has been illustrated several preferred embodiments of the invention while the appended claims are intended to cover other variations and modifications thereof which fall within the scope and spirit of the invention.

In the drawings:

Fig. 1 is a bottom plan view of the arch plate 20 with the tension plate and shoe shown in broken lines.

Fig. 2 is a longitudinal sectional view through the arch support and shoe taken approximately on the line indicated at 2—2 in Fig. 1.

Fig. 3 is a bottom plan view similar to Fig. 1, showing the tension plate in full lines.

Fig. 4 is a transverse sectional view through the shoe and arch support taken approximately on the line 4—4 of Fig. 3.

Fig. 5 is a bottom plan view of an arch support illustrating a modified form of the tension plate and adjusting means therefor.

Fig. 6 is a bottom plan view of a further modification of the invention.

Fig. 7 is a longitudinal sectional view through a shoe and arch support illustrating the metatarsal arch support combined with the arch support and tension plate.

Referring to the drawings by characters of reference, A designates the sole of a shoe, B the heel and C the arch support which overlies the forward portion of the heel and which extends forwardly thereof to a point in front of the metatarsal arch underlying and supporting the 45 metatarsal arch and the longitudinal and transverse arches.

The arch support C includes a longitudinal arch plate 10 which may be constructed in any desired manner to provide areas or portions having different degrees of flexibility or resiliency, the area or portion having the greatest resistance to flexing or bending and which is the highest region in the arch of the plate, is located adjacent to the inner side edge thereof and under- 50 55

lies the inner longitudinal arch, with areas or portions thereof of increasing flexibility or resiliency merging one with the other and extending forwardly and rearwardly to the end edges of the plate and to the opposite side edge thereof.

In the embodiment of the invention illustrated, the arch plate 10 is composed of a plurality of thin spring metal or equivalent flexible plies or laminations 11, 12, 13, 14, 15, 16 and 17, each of which is connected at its edge to its adjacent ply or plies to provide a resilient laminated assembly having areas of varying degrees of flexibility. The topmost ply or lamination 11, at its side edges, conforms to the shape of the "last" of the shoe in the region of the instep and at its forward end is recessed at 18 to provide forwardly extending divergent or forked portions 19 and 20, which portions are formed as continuations of the inner and outer sides of the arch plate assembly and extend in the direction of and underlie the inner and outer longitudinal arches of the foot.

The rear of the outer side edge 21 of the topmost ply 11 curves inwardly and merges into the rear edge which extends across the shoe structure in the region of the heel portion B in a rearward direction, the rearmost point then merging into the opposite inner side edge 23. The next adjacent underlying ply 12 follows generally the contour of the ply 11 and has forked or divergent forward ends 24 and 25, the former being of substantially the same shape as the corresponding portion 19 of the plate 11 but terminating slightly in rear thereof and being unsecured thereto but adapted to bear thereagainst. The forked end 25 of the ply 12 is of lesser size and length than the portion 20 of the ply 11 and bears thereagainst but is not secured thereto. The outer side edge 26 of the ply 12 extends diagonally and rearwardly towards the inner side edge 23 of the ply 11 and said edge 26 is spaced a substantial distance from the edges 21 and 22 of the plate 11 and has concavities adjacent its forward and rear ends which merge into a medial convexity. The rearmost portion of the ply 12 is spaced slightly in advance of the rearmost portion of the edge 22 of the plate 11. The marginal edge 26 and the inner side edge which corresponds to the edge 23 of the ply 11 is spot welded or otherwise secured to the ply 11 as at 27 and also along a line extending across the forked portion 25 as illustrated.

The remaining plies 13 to 17 inclusive are of generally similar contour but of progressively smaller size and the plies 13 and 14 have forwardly projecting portions 28 and 29 at their inner sides with the latter portion 29 underlying the portion 28 and with the portion 28 underlying the portion 24, which portions are unsecured in order that the arch plate may freely flex in this region.

The remaining marginal edges of the plies 13 and 14 and the entire marginal edges of the plies 15, 16, and 17 are spot welded or otherwise secured to the next adjacent ply or plies as shown to provide a laminated assembly with the inner side edges of all of the plies disposed flush with each other.

The arch supporting structure further includes a tension plate 30, which in the embodiment illustrated in Figs. 1 to 4 inclusive, has a forward portion 31 so contoured as to permit of the contact of the foot with the insole of the shoe at the bases of the great and little toes and which underlies the forked portions 19 and 20 and has

a forward convex edge 32 extending between the forward ends of the forked portions which are welded or otherwise secured thereto as at 33. The tension plate 30 is of gradually decreasing width from the forward portion 31 towards the rear and has an inner concave side edge 34 which follows substantially the shape of the insole and which, together with the opposite concave side edge 35, defines a rearwardly directed diagonal terminal 36 which terminates at the juncture of the rearmost portion of the rear edge 22 with the inner side edge 23 of the ply 11 and is spot welded or otherwise secured thereto as at 37.

The arch plate may be adjusted in any desired manner by increasing or decreasing the degree of curvature of the tension plate 30 and as shown in this form of the invention, a headed stud 38 is secured to the underside of the tension plate and has an internally threaded hollow shank 39 depending therefrom and extending into a sleeve 40 which is located in an opening in the shank portion of the sole A of the shoe. A screw shank 41 threadedly engages within the threaded bore of the shank 39 and has its kerfed head disposed in an opening 42 in a face plate 43 countersunk in the underside of the shank portion of the shoe, the sleeve 40 extending through an opening formed in one or more spring leaves 44 which bears on the upper surface of the shank portion of the shoe with the upper end of the sleeve beaded or flanged to overlie the leaf 44 as at 45. The spring leaf 44 and face plate 43 are suitably anchored to the shank portion of the shoe. The screw 41 between the kerfed head and the shank thereof is formed with an enlarged circular flange 47 disposed between the face plate 43 and the lower end of the sleeve so that the screw 41 is free to turn or move the stud 38 vertically, while retained against axial movement. Vertical movement of the stud 38 may be thus effected by turning of the screw 41 which movement produces a corresponding flexing of the tension plate 30 to vary the curvature of the arch plate. In this form of the invention also it is apparent that adjustments may be made in the degree of curvature of the arch plate while the shoe is being worn, by varying the curvature of the tension plate through the medium of the screw 41.

In the form of the invention illustrated in Fig. 5, the uppermost ply 11' is anchored adjacent its rear end as by a stud 50 which extends downwardly through an opening in the ply 11' and is secured in the shank portion of the sole. In this form of the invention also the rear portion of the tension plate 30' terminates in spaced relation with the rear edge 22' of the ply 11' but which is adjustably connected with the plate assembly 10' to vary the height and curvature thereof. As shown, the adjustable connection includes a pair of sleeves 51 and 52 having oppositely directed forked shanks 53 and 54 which are spot welded or otherwise secured to the underside of the rear portions of the tension plate 30' and the plate assembly 10' respectively with the sleeves 51 and 52 spaced apart and provided with longitudinally aligned threaded bores to receive the opposite ends of a threaded screw 55, one end of which is provided with a right hand thread and the other end with a left hand thread, the sleeves 51 and 52 being correspondingly threaded. The screw 55 is provided with an enlarged medial head 56 having one or more apertures 57 to receive therethrough a lock or cotter pin 58 by means of which the screw 55 may be secured against turning when the same has been adjusted.

to effect the degree of tension desired between the opposite ends of the spring leaf assembly so as to produce the required degree of curvature in the arch plate. In order to further lock the screw 55, a lock nut 59 is provided on one of the threaded ends of the screw 55 for engagement against the end of the sleeve 54.

In the form of the invention illustrated in Fig. 6, the uppermost ply 60 of the arch plate, which corresponds to the ply 11 in the other forms, extends rearwardly to overlie the entire heel portion of the shoe structure, while the remaining plies are identical with those in the other forms of the invention. In this instance, the arch plate is anchored at 61 and 62 to the shoe structure and the tension plate 63 is formed with the rearwardly extending terminal 64 which has welded or otherwise secured to its rearmost portion an internally threaded sleeve 65 which depends therefrom. A threaded shank 66 of a screw engages in the sleeve 65 and extends rearwardly through an opening 67 in the heel structure 68 of the shoe. The screw shank 66 is provided with a kerfed head 69 and an enlarged flange 70, the head lying within an opening 71 in a plate 72 recessed in the rear face of the heel structure 68 and anchored in place by screws 73 which are threadedly engaged in sleeves 74 secured within the heel structure. The flange 70 is located in a recess 75 in the heel structure and is covered by the plate 72. Adjustments in the tension plate 63 are effected by turning the screw shank 66 to increase or decrease the curvature of the arch plate 60.

In the various forms of the invention illustrated, the arch plate which supports the inner and outer longitudinal and transverse arches may also be provided with means for supporting the metatarsal arch and as shown in Fig. 7, the metatarsal arch supporting means consists of a yieldable resilient pad 80 which overlies the forward portion of the tension plate and is exposed for contact with the metatarsal region of the foot by the recessed forward portion of the arch plate 16. As particularly illustrated, the tension plate has secured thereto a yieldable element 81 which defines together with the tension plate a pocket having an entrance mouth 82 disposed rearwardly for permitting of the introduction of the pad 80 thereto and the removal of the same therefrom in order to interchangeably employ pads of varying shapes and sizes. Under this construction and arrangement, it is apparent that an arch support has been devised which combines in a single structure adjustable means for supporting the longitudinal and transverse arches as well as the metatarsal arch of the foot.

What is claimed is:

1. An arch support for shoes including an arch plate so constructed and arranged as to provide portions thereof having relatively different degrees of thickness and varying degrees of flexibility with the greatest thickness and resistance to bending being located in the highest region in the arch of the plate and with areas of lesser thickness and increasing flexibility merging one with the other and extending forwardly and rearwardly thereof to the end edges of the plate, a flexible tension plate fixedly connected with the arch plate adjacent the opposite ends thereof, and means for tensioning said tension plate for effecting a differential upward arching of the arch plate.

2. An arch support for shoes including an arch plate so constructed and arranged as to provide

portions thereof having relatively different degrees of thickness and varying degrees of flexibility with the greatest thickness and resistance to bending being located in the highest region in the arch of the plate and with areas of lesser thickness and increasing flexibility merging one with the other and extending forwardly and rearwardly thereof to the end edges of the plate, a tension plate fixedly connected at one end with the arch plate and means connected with said tension plate so as to effect a longitudinal stress on the arch plate between its ends and an upward arching of said arch plate.

3. An arch support for shoes including an arch plate having its forward medial portion recessed to provide forwardly divergent extensions of the inner and outer side portions of the plate which extend in the direction of and underlie the inner and outer longitudinal arches of the foot, the said plate being further so constructed and arranged as to provide portions thereof having relatively different degrees of thickness and varying degrees of flexibility, the greatest thickness and resistance to bending being located adjacent the inner side edge of the plate and in the region of the highest portion of the arch plate and with portions thereof of lesser thickness and increasing flexibility merging one with the other and extending forwardly thereof to the end edges of said extensions, a tension plate fixedly connected to the forward end of said extensions, and means for tensioning said tension plate for effecting a differential upward arching of the arch plate.

4. An arch support for shoes including an arch plate composed of a plurality of flexible plies connected together and so contoured as to provide a resilient laminated assembly having portions thereof of varying degrees of flexibility, with the greatest resistance to bending being located in the region of the highest portion of the arch plate and with portions thereof of increasing flexibility merging one with the other and extending forwardly and rearwardly thereof to the end edges of the plate, a flexible tension plate fixedly connected with the arch plate adjacent the opposite ends thereof, and means for tensioning said tension plate for effecting a differential upward arching of the arch plate.

5. An arch support for shoes including an arch plate composed of a plurality of flexible plies connected together and so contoured as to provide a resilient laminated assembly having portions thereof of varying degrees of flexibility, with the greatest resistance to bending being located in the region of the highest portion of the arch plate and with portions thereof of increasing flexibility merging one with the other and extending forwardly and rearwardly thereof to the end edges of the plate, a tension plate fixedly connected at one end with the arch plate, and means connected with said tension plate so as to effect a longitudinal stress on the arch plate between its ends to effect a differential upward arching of the said arch plate.

6. An arch support for shoes including an arch plate composed of a plurality of flexible plies connected together and so contoured as to provide a resilient laminated assembly having portions thereof of varying degrees of flexibility, with the greatest resistance to bending being located adjacent the inner side edge of the arch plate in the region of the highest portion of the arch plate and with portions thereof of increasing flexibility merging one with the other and extending for-

wardly and rearwardly thereof to the end edges of the arch plate and to the opposite side edge thereof, a tension plate fixedly connected at one end with the arch plate, and means connected with said tension plate so as to effect a longitudinal stress on the arch plate between its ends to effect a differential upward arching of the said arch plate.

7. An arch support for shoes including an arch plate composed of a plurality of flexible plies secured together and so contoured as to provide a resilient laminated assembly having portions thereof of varying degrees of flexibility certain of said plies having their forward portions recessed to provide forwardly divergent extensions a tension plate fixedly connected to the forward ends of said extensions, and means connected with said tension plate so as to effect a longitudinal stress on the arch plate between its ends to effect a differential upward arching of said arch plate.

8. An arch support for shoes including an arch plate having its forward medial portion recessed

to provide forwardly directed extensions of the inner and outer side portions of the plate, a tension plate fixedly connected to the forward ends of said extensions, means connected with said tension plate so as to effect a longitudinal stress on the arch plate between its ends to produce an upward arching of the arch plate, and yieldable resilient means arranged upon the forward end of said tension plate between the said extensions for supporting the metatarsal arch of the foot.

9. An arch supporting accessory for shoes including a flexible resilient arch plate, a flexible resilient stress plate fixedly connected with the arch plate adjacent the opposite ends thereof and adapted upon flexing of the stress plate to exert a compression on the arch plate between its ends for effecting a differential arching of the arch plate, and means cooperating with the stress plate for flexing the same, said latter means being carried by the shoe and adjustable from the exterior thereof.

JOSEPH C. HOWELL.
